SPOOL ADJUSTING MEANS

Frederic E. Banfield, Jr., Whitinsville, Mass., assignor to Whitin Machine Works, Whitinsville, Mass., a corporation of Massachusetts

Application July 26, 1940, Serial No. 347,702

5 Claims. (Cl. 57—130)

This invention relates to spindles used in spinning, twisting or winding operations. When such spindles are in use, and particularly when used with rayon or other synthetic fibers, it is desirable that the spool on the spindle be so positioned vertically that the lower limit of yarn traverse will be in correct vertical relation to the top surface of the lower head of the spool. If the spool is not so positioned, the yarn will be wound irregularly at the lower end of the traverse and will frequently bind or break while being unwound from the spool.

It is the general object of my invention to provide improved spool-adjusting means by which the spool may be accurately positioned vertically.

A further object is to provide improved spool-supporting means which can be adjusted without removing any part of the spindle from operative position, and even without stopping the frame.

A further object is to provide a construction by which the amount of vertical spool adjustment can be accurately predetermined.

Preferred forms of my invention are shown in the drawings, in which

Fig. 1 is a sectional side elevation of a twister spindle and associated parts, with my invention embodied therein;

Fig. 2 is a side elevation of a portion of the spindle, partially broken away;

Fig. 3 is a plan view of a spool-supporting member or cap, looking in the direction of the arrow 3 in Fig. 2;

Fig. 4 is a sectional side elevation of said member, taken along the line 4—4 in Fig. 3;

Fig. 5 is a plan view of an adjusting ring which coacts with said spool-supporting member;

Fig. 6 is a sectional side elevation thereof, taken along the line 6—6 in Fig. 5;

Fig. 7 is a sectional side elevation, showing my invention applied to a somewhat different type of spindle;

Fig. 8 is a side elevation of a portion of a spindle, partly in section and showing a modified construction; and

Fig. 9 is a view similar to Fig. 8 but showing a further modification.

Referring to Figs. 1 to 6, I have shown my invention embodied in a spindle comprising a base 10 secured in a fixed frame member 11 by a clamping nut 12. A bolster 14 is mounted in an upward extension of the base 10 and is held in fixed vertical position by coacting shoulders on the bolster and base, as indicated at 15.

A spindle blade 17 is mounted in the bolster 14

and is rotatably supported in a definite vertical position by a ball bearing having its inner race 18 fixed on the blade 17 and its outer race 19 fixed in the bolster 14.

A belt-driven whirl 20 is fixed on the blade 17 above its supporting bearing and rotates outside of the upper part of the base and bolster. The usual doffer guard 22 prevents upward displacement of the spindle, and the usual brake lever 23 and brake 24 provides means for stopping the spindle without stopping the remaining spindles on the frame. The lower end 25 of the blade 17 has a cylindrical bearing in the lower end of the bolster 14 but has no step bearing therein.

The usual traveler T rotates on a twister ring R carried by the vertically reciprocated ring rail 30. The yarn Y is guided by the traveler T to a spool S mounted on the blade 17 and on which the yarn is wound.

My present invention relates particularly to improved means for vertically adjusting the spool S so that the upper surface 31 of the lower head 32 of the spool will be in correct vertical relationship with the yarn-guiding portion of the traveler T, when the ring rail 30 is at the bottom of its traverse.

For this purpose, I provide a spool-supporting cap 40 loosely mounted on a cylindrical upper portion 41 of the whirl 20. Driving lugs 42 are formed on the top of the cap 40 and engage radially disposed slots in the lower surface of the spool S to form the usual spool-driving connection.

The lower edge of the cap 40 is formed with a plurality of segmental helical surfaces 43 on which downwardly projecting teeth 44 are provided. The number of these segmental surfaces may be varied but three such surfaces are shown in the drawings.

A ring 50 is fixed on the lower part of the cylindrical portion 41 of the whirl 20 and is provided with segmental surfaces 51 having upwardly projecting teeth 52, as shown in Figs. 2 and 6. The surfaces 51 and teeth 52 coact with the surfaces 43 and teeth 44 to vertically position the cap 40.

Binding screws 54 are provided in the cap 40 and may be used if desired to retain an adjusted angular relation between the cap 40 and whirl 20. Under ordinary conditions, however, these parts will retain their adjusted position, even if the binding screws 54 are not used.

The method of operation and advantages of my improved construction will be readily apparent. By lifting the cap 40 to clear the teeth 52 of the

ring 50, the cap may be turned through any desired angle. When again seated on the ring 50, the cap will have been raised or lowered a definite amount, depending on the direction and angle through which the cap has been turned. In Fig. 2 the parts are shown after the cap has been raised by an amount equal to a single tooth adjustment.

This adjustment can be made without removing the spool from the spindle and without removing the spindle blade or any other part of the spindle from the base 10. Furthermore, by applying the brake 24, the spindle may be held from rotation during adjustment and the adjustment may be made without stopping the other spindles on the frame.

In this manner, vertical adjustment of each spool may be quickly and accurately made and positively retained, and removal of parts or interruption of machine production is entirely avoided.

In Fig. 7 I have shown my invention embodied in a spindle of a somewhat different type, in which a blade 60 is rotatable in an upper bearing 61 and lower bearing 62 in a bolster 63, and in which also the vertical relation of the blade 60 to the bolster 63 is determined by a step bearing 64. The vertical position of the bolster in the base is also determined by a step bearing 65. A whirl 67 is fixed to the blade 60, as previously described. The spool-supporting cap 68 and toothed ring 69 are of the construction shown in Figs. 3 to 6 and operate in precisely the same way in providing vertical adjustment for a spool mounted on the spool-supporting member or cap 68.

In Fig. 8 I have shown a modified construction, in which a whirl 70 is fixed on a spindle blade 71 and is provided with a threaded portion 72. A spool-supporting cap 73 is provided with an internally threaded portion 74 engaged with the threaded portion 72 to determine the height of the cap 73. Driving lugs 75 are formed on the top surface of the cap 73 as previously described, and one or more clamping screws 76 are provided to maintain the parts in an adjusted angular relation. By turning the cap 73 on the threaded portion 72 of the whirl 70, the cap may be raised or lowered to any desired extent, and the adjustment can be retained by tightening the screws 76.

This method of adjustment does not provide the positive lock of the toothed construction previously described, but on the other hand it permits finer adjustment than is possible with the toothed construction.

A further modification is shown in Fig. 9, in which a whirl 80 is mounted on a blade 81 and is provided in its upper part with a threaded portion 82 and a cylindrical portion 83. Driving lugs 84 are formed on the upper face of the cylindrical portion 83, so that the spool drive is not transmitted through circumferentially adjustable parts.

A spool-supporting ring 86 is threaded on the part 82 of the whirl 80 and is rotatable about the cylindrical portion 83 of said whirl. A spool

is supported on the upper surface 87 of the ring 86, and the ring may be held in angularly adjusted position by one or more screws 88.

This construction preserves the fineness of adjustment found also in the construction shown in Fig. 8, but the ring 86 merely supports the spool and has no spool-driving function, being in this respect an improvement over the construction shown in Fig. 8.

10 Both of the modified structures shown in Figs. 8 and 9 may be adjusted without removing the spool or any part of the spindle from the frame, and may also be adjusted if desired without stopping the rotation of other spindles in the frame.

15 It will be understood that the word "spool" as used herein includes bobbins also.

Having thus described my invention and the advantages thereof, I do not wish to be limited 20 to the details herein disclosed, otherwise than as set forth in the claims, but what I claim is:

1. In a textile machine, a spindle having a rotated blade, a spool mounted on and rotated with said blade, a member which supports said spool on said blade, and means to change the axial position of said member relative to said blade by selective segmental adjustments of predetermined amount.

2. In a textile machine, a spindle having a rotated blade, a spool mounted on and rotated with said blade, a support for said spool on said blade, coacting segmental helical elements fixed relative to said support and blade and constituting axial adjusting means for said support, and locking means to positively retain an adjusted angular relation of said support to said blade.

3. In a textile machine, a spindle having a rotated blade, a spool mounted on and rotated with said blade, a driving whirl fixed to said spindle, and a spool-supporting cap rotatably mounted on said whirl, said cap and whirl having a plurality of coacting segmental helical surfaces together making up a circumference and each extending not over 180° and which, when relatively adjusted angularly, change the axial relation of said cap and blade.

4. In a textile machine, a spindle having a rotated blade, a spool mounted on and rotated with said blade, a support for said spool on said blade, means to change the relative axial relation of said support and blade by a change in the angular position of said support relative to said blade, and toothed means to positively lock said support to said blade in any selected one of a plurality of different angular positions relative thereto.

5. In a textile machine, a spindle having a rotated blade, a spool mounted on and rotated with said blade, a whirl to drive said blade, and a spool-supporting member mounted on said whirl, said whirl and member having coacting toothed helical portions constituting axial adjusting and locking means for said member on said whirl and blade.

FREDERIC E. BANFIELD, JR.
